IGNITION LOCK HOUSING

Sam Barmherzig, 1457 E. 86th St.,
Brooklyn, N.Y. 11236

Filed June 21, 1973, Ser. No. 372,277

Term of patent 14 years

Int. Cl. D8—07

U.S. Cl. D8—113

FIG. 1

FIG. 2

FIG. 5

FIG. 3

FIG. 4

FIG. 6

FIG. 1 is a perspective view of my new design for an ignition lock housing;

FIG. 2 is a top plan view thereof;

FIG. 3 is a left side elevational view thereof;

FIG. 4 is a bottom plan view thereof;

FIG. 5 is a front elevational view thereof; and

FIG. 6 is a rear elevational view thereof.

The side opposite that shown is substantially the same as the side that is shown.

I claim:

The ornamental design for an ignition lock housing, substantially as shown and described.
